UNITED STATES PATENT OFFICE.

EDWARD B. TYLER, OF PITTSBURGH, PENNSYLVANIA.

PIPE-SUPPORT.

1,097,273.

Specification of Letters Patent.

Patented May 19, 1914.

Application filed November 25, 1913. Serial No. 802,923.

To all whom it may concern:

Be it known that I, EDWARD B. TYLER, a citizen of the United States, and a resident of Pittsburgh, in the county of Allegheny and State of Pennsylvania, have invented a new and useful Improvement in Pipe-Supports, of which the following is a full, clear, and exact description, reference being had to the accompanying drawings, forming 10 part of this specification, in which—

Figure 1 is a transverse vertical section of a conduit showing a plurality of my improved pipe supports therein; Fig. 2 is a transverse section through one of the supporting devices; and Fig. 3 is a perspective view of one of the supporting devices.

My invention has relation to supports for pipes, and more particularly to supports designed to be used for carrying heat 20 conveying pipes in conduits or along the walls of factories and other large buildings.

The object of the invention is to provide a support of this character which is simple and comparatively inexpensive; which is 25 adapted to a wide variety of work; which can be used for supporting either one or a plurality of pipes side by side, and which, when used for more than one pipe, will enable the pipes to be placed closely together; 30 which provides for free adjustment, and which is of a character to relieve the pipe lines from lateral strains.

The nature of my invention will be best understood by reference to the accompanying drawing in which I have shown the preferred embodiment thereof, and which will now be described, it being premised that various changes can be made in the details of construction and arrangement of the parts 40 without departing from the spirit and scope of my invention as defined in the appended claims.

In this drawing the numeral 2 designates a bracket having a vertical securing arm by 45 means of which it can be attached to a post, such as indicated at 3, or to any other suitable support. The bracket also has a horizontally extending supporting arm 4 formed with a slide-way 5, the lateral walls of 50 which are of dovetailed, or undercut, form as indicated at 6.

7 designates a plate having a dovetailed projection 8, which is fitted to the slide-way 5 to be moved on the supporting arm 4. 55 The upper surface of the plate 7 is formed

with a plurality of parallel slide-ways 9 (three such slide-ways being shown in the present instance). These slide-ways are preferably formed with beveled or undercut lateral walls, and are adapted to receive 60 therein the pipe supporting chairs 10. These chairs may be of any desired form. As shown herein, each chair consists of two separated chair portions connected by a transverse web 11, and having the legs 12 65 which are adapted to the slide-ways 9. The outer surfaces of the outer legs 12 are shown as beveled to engage the undercut walls of the slide-ways 9. Each of the chair portions is shown as having an oblique upper surface in which is formed a cavity arranged to seat an antifriction ball 12^a. These balls form a direct support for the pipes. The chairs may be prevented from entirely moving out of the slide-ways 9 by 70 means of suitable pins 9^a at the outer ends of the slide-ways. 75

In Fig. 1 I have illustrated a plurality of the supports arranged within a conduit 13, the supporting post 3 being centrally located within the conduit. This post may be provided with a continuous vertical slot 14 for the securing bolts 15 of the several brackets 2. By slackening the nuts of these bolts, the several brackets can be readily 85 adjusted in the slot to the desired heights. In this figure I have shown one of the brackets 2 as supporting two pipes; another as supporting a single pipe; and the third one as supporting three pipes. Where more 90 than one pipe is supported, I preferably place the chairs 10 for the several pipes in the different slide-ways of the plate 7. If the three chairs were placed in the same slide-way in Fig. 3, or at the right hand 95 side of Fig. 1, it is obvious that the several pipes could not be placed as closely together. By placing the chairs in different slide-ways their leg portions can be overlapped, thereby bringing the pipes much 100 closer together. The sliding plate 7 provides for considerable lateral adjustment; and the lateral movement of this plate, together with the fact that the chairs 10 are capable of movement in their respective 105 slide-ways, relieves the pipe lines, both individually and collectively, from side strains which might otherwise occur, due to lack of alinement between adjacent supports, or to other causes.

It will be understood that the brackets 2 can be secured to any desired support either within a conduit or at any other desired place. It will also be obvious that the form 5 of the bracket can be changed as may be desired.

I claim:

- 10 1. A pipe support comprising a bracket, a supporting plate slidably mounted for horizontal movement on the bracket, and a pipe supporting chair slidably mounted on said plate, said chair having ball supports for a pipe; substantially as described.
- 15 2. A pipe support comprising a bracket, a supporting plate slidably mounted for horizontal movement on the bracket, and a pipe supporting chair slidably mounted on said plate; substantially as described.
- 20 3. A pipe support comprising a bracket, a plate slidably mounted on the bracket, and a plurality of pipe supporting chairs slid-

ably mounted on said plate; substantially as described.

4. A pipe support comprising a supporting member, a plate slidably mounted on 25 said member and having a plurality of parallel slide-ways on its upper surface, and pipe supporting chairs adapted to said slide-ways; substantially as described.

5. A pipe support comprising a supporting member, and a plate slidably mounted thereon, said plate having a plurality of slide-ways therein, said slide-ways being arranged side by side in substantially parallel 30 relation; substantially as described. 35

In testimony whereof, I have hereunto set my hand.

EDWARD B. TYLER.
